Earl K. Stewart, Schenectady, N.Y., assignor to General
Electric Company, a corporation of New York

Filed Aug. 31, 1966, Ser. No. 3,665

Term of patent 14 years

(Cl. D26—15)

FIG. 1

FIG. 2

FIGURE 1 is a perspective view of an electrical transformer, showing my new design;

FIGURE 2 is a front elevational view;

FIGURE 3 is a side elevational view, the opposite side being substantially a mirror image; and

FIGURE 4 is a rear elevational view thereof.

The bottom, not shown, is a conventional substantially flat unornamented surface.

I claim:

The ornamental design for an electrical transformer or similar article, as shown and described.
